CLAIM

The ornamental design for a fringe mop, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a top view of a fringe mop showing my new design; FIG. 2 is a bottom view thereof;

FIG. 3 is a top-side view from a first perspective thereof; FIG. 4 is a top-side view from a second perspective thereof;

FIG. 5 is a bottom perspective view thereof;

FIG. 6 is a top perspective view thereof;

FIG. 7 bottom-side view from a first perspective thereof; and,

FIG. 8 bottom-side view from a second perspective thereof. The colors and color contrasts form part of the claimed design.
